(57) **CLAIM**

The ornamental design for a wireless access point, as shown and described.

DESCRIPTION

FIG. 1 is a front view of a wireless access point according to a first embodiment of our new design;

FIG. 2 is a back view of the wireless access point shown in FIG. 1;

FIG. 3 is a left view of the wireless access point shown in FIG. 1;

FIG. 4 is a right view of the wireless access point shown in FIG. 1;

FIG. 5 is a top view of the wireless access point shown in FIG. 1;

FIG. 6 is a bottom view of the wireless access point shown in FIG. 1;

FIG. 7 is a perspective view of the wireless access point shown in FIG. 1;

FIG. 8 is another perspective view of the wireless access point shown in FIG. 1;

FIG. 9 is a front view of a wireless access point according to a second embodiment of our new design;

FIG. 10 is a back view of the wireless access point shown in FIG. 9;

FIG. 11 is a left view of the wireless access point shown in FIG. 9;

FIG. 12 is a right view of the wireless access point shown in FIG. 9;

FIG. 13 is a top view of the wireless access point shown in FIG. 9;

FIG. 14 is a bottom view of the wireless access point shown in FIG. 9;

FIG. 15 is a perspective view of the wireless access point shown in FIG. 9; and,

FIG. 16 is another perspective view of the wireless access point shown in FIG. 9.
